UNITED STATES PATENT OFFICE

ROBERT F. RINGLE, OF ZELIENOPLE, PENNSYLVANIA

MOLDING MACHINE

Application filed December 5, 1927. Serial No. 237,630.

My invention relates to improvements in molding machines of the type used for agitating a mold and its flask for jarring, so as to tamp the sand evenly and compactly around the pattern. The machine is generally similar to that shown in prior patent of Herman et al. #908,002, issued Dec. 29, 1908.

The present improved construction has in view to provide means for maintaining the working table in vertical alinement with the supporting base, with exclusion of impurities in the atmosphere and also for continuously maintaining an accurate sliding fit at the corner portions of the machine. Also, to provide a large flat continuous impact surface for the table, for absorption of the shock on its downward movement, with means for retaining the impact elements in operative relation, and for restraining the table from undue upward movement, with other features of detail construction, as shall be more fully hereinafter described.

Generally stated, the machine comprises a foundation base or frame, having a centrally arranged cylinder, a vibrating table provided with a plunger mounted in the cylinder, an automatically operating valve for admitting and releasing pressure to and from the cylinder for alternate operation of the plunger and table, together with suitable lubricating means, and the features above particularly noted.

Referring to the drawings showing one preferred embodiment of the invention,—

Fig. 1 is a central vertical section through the machine showing it in lowered position, on the line I—I of Fig. 2;

Fig. 2 is a plan view of the base, the table and plunger having been removed;

Fig. 3 is an enlarged sectional detail view showing the sliding bearing construction at the corner portion of the table, on the line III—III of Fig. 2;

Fig. 4 is a horizontal section, on the line IV—IV of Fig. 5;

Fig. 5 is a vertical sectional view, on the broken line V—V of Fig. 2.

The main base portion 2 of the machine consists of a rectangular casting adapted to be mounted on a suitable supporting foundation 3 in which base is centrally carried the cylinder 4 with a vertically reciprocating plunger 5. The cylinder 4 is located within a central annular cavity of the main base 2 depending therefrom by an upper annular flange 6 by which it is secured by any suitable means, as bolts. The base 2 is amply braced and supported by interior and exterior ribs and partitions, the interior partitions being preferably provided with transverse openings for air circulation whereby to allow for ample incoming and outgoing air and avoiding objectionable partial vacuum due to the rapid reciprocation of the jarring table.

The outer portion of the base extends upwardly above a middle transverse floor portion 8 by outer walls 9 between which the jarring table extends downwardly for bumping action by its transverse bottom plate 14 against an intervening transverse jarring plate 10. Plate 10 is laid across the entire floor portion 8 of the machine, with middle clearance for the plunger cylinder, and with an intervening comparatively thin sheet 11 of suitable shock absorbent material, as fibre, cork or the like, whereby to absorb the shocks of impact.

The jarring table 12 extends across the entire upper portion of the supporting frame by its upper table top and is provided with a downwardly extending interior skeleton framework 13. The latter is provided with the supporting bottom 14 adapted to make contact with the jarring plate 10, and is alternately raised by the plunger 5 and lowered by gravity upon admission and exhaust of a suitable fluid under pressure. The middle interior portion of the table 12 is provided with an annular frame or ring 15 against

which abuts and to which is secured the upper flange 16 of the plunger 5.

The plunger is alternately raised and lowered by admission of fluid under pressure through the valve A, the stem of which is lifted and lowered by the connecting yoke 17 of the valve secured as at 18 in the lower body portion of the table at one side of the plunger cavity.

10 The stem 19 of the valve is connected with the cylindrical slide valve 20 by its terminal having the nut 21 and collar 22 providing for a limited amount of lost motion at each side of the middle collar 23 of the valve. The 15 stem 17 being connected with the table will rise with the rise of the table under pressure, cutting off the pressure supply through inlet pipe B and opening the exhaust ports for escape of the previously used pressure fluid 20 through exhaust pipe C upon alternate lowering of the table. Likewise, lowering of the table, after a limited amount of lost motion of stem 19, will shift the valve 20 downwardly, closing the exhaust ports and opening the 25 supply for another lifting operation.

The corner wall portions 9 of the main base provide outer guiding housings for the table, which is provided at each corner with the wearing faces 24 planed at right angles 30 to each other and providing for vertical guiding movement within coacting wearing plates 25. The wearing plates 25 are mounted within the upwardly extending corner wall portions 9 by means of series of upper and lower 35 studs and bolts 26, 27, respectively. The contacting faces of such plates, with the corner faces 24 of the table, are accurately fitted for vertical sliding movement one against the other, during vertical reciprocation of the 40 table throughout its limited range of movement.

For the purpose of protecting the interior of the construction and preventing access of dust or other foreign matter to such wearing 45 faces, I provide outer enclosing covering plates 28 of thin sheet or plate metal, screwed to the edges of table 12 as shown, and extending downwardly over the outer portion of walls 9 so as to slide thereon with a close fit, 50 effectually excluding such objectionable impure air circulation. The upper outer edge portion of wall 9 is preferably planed or faced as at 29 to provide a smooth wearing fit for the reciprocating closing plate 28 in 55 its upward and downward movement.

The working faces 24 are furnished with lubricant at suitable points, by the terminals 39 of the lubricating system more fully described in my companion application, Serial 60 No. 237,629.

For the purpose of loosely retaining the impact or jarring plate 10 in operative position, and in continuous bearing contact against the shock absorbent blanket 11, I 65 provide a series of retaining studs 30 which

extend upwardly through the top plate 8 of the base and are tapped into the plate 10 at suitably arranged locations, as at 31. Studs 30 extend downwardly through the blanket 11 and loosely through holes in base plate 8 and are provided with nuts 32 and cushioning springs 33. A number of such studs are symmetrically arranged around the middle of the machine, as in Fig. 2, and operate to continuously hold the impact plates together or to restrain them against any material upward movement due to suction or other causes.

Likewise, for the purpose of restraining the table from any undue upward movement, I 80 provide the safety rods 34 shown in Fig. 5. These are located in the manner shown, one at each side of the center, and extend upwardly through openings 35 in base plate 8 and are secured as by screw threads in the lower impact plate 7 of the table, as indicated at 36. The bolts 34 extend downwardly through the impact plates and the base, and are provided with terminal heads 37 and short cushioning springs 38.

85 Springs 38 are comparatively short and are adapted to allow for the desired limited range of upward movement of the table under jarring action of the valve-controlled plunger, and to then come into contact with the under side of the base plate or reinforced lugs thereon to restrain and cushion further upward movement.

90 By such means the normal table movement is regulated and limited so as to avoid any undesired excess travel. The springs likewise assist in effecting a quick rebound or downward movement of the table upon release of the pressure beneath the plunger.

With the machine operating in the manner intended, with continuous alternate vertical reciprocations, and with the accurate guiding and limiting action of the means above described, together with proper lubrication, it will continue to function efficiently, avoiding 100 wear, with protection of the parts from intrusion of sand or other gritty foreign material. The absorption of the shocks of impact is effected by the broad area provided by plate 10 and blanket 11, and the operation is 105 greatly improved and the noise resulting therefrom is materially reduced, while adding to the regularity of operation otherwise.

An important object of the invention is to 110 provide for ample air circulation through the interior of the machine, to compensate for suction and compression resulting from the reciprocation of the table within the closure effected by plates 28.

115 Thus, as the table rises above floor 8, it will tend to create a retarding vacuum, and to compress the air on downward stroke, with objectionable resistance to free movement in either direction. I obviate these objections 120 by providing air circulation or "breathing"

openings and passages through the base and its floor upwardly to the table containing cavity, with means providing for a clean air supply.

5 For such purpose one or more clean air conduits 40 are connected through opening 41 in the outer wall of the main base 2. The interior reinforcing walls 42 of the base are transversely apertured as at 43 for free air circulation, and at suitable points the floor 8 is provided with similar circulating openings 44. By this means there is a constant free open communication from above the floor, or the table cavity, to the outside atmosphere, so that as the table moves up and down, any tendency to suction and partial vacuum, or compression, is completely avoided. By filtering or screening the air entering conduit 40, all sand or other foreign matter is excluded.

20 The jarring plate 10 and blanket 11 are so shaped at their inner edge portions around the plunger cylinder as to leave the openings 44 uncovered, without materially reducing the bearing area of the jarring plate and blanket.

25 What I claim is:—

1. In a molding machine, the combination with a supporting base having a central plunger cavity, outer upwardly projecting walls, an intervening flat bearing surface, and 30 a reciprocable table thereon, of a continuous flat layer of shock absorbing material laid on the flat bearing surface of the base, a superimposed impact plate thereon for contact with the table, and spring retracted bolts engaging the impact plate.

2. In a molding machine, the combination with a supporting base having a central plunger cavity, outer upwardly projecting walls, an intervening flat bearing surface, and 40 a reciprocable table thereon, of a continuous flat layer of shock absorbing material laid on the flat bearing surface of the base, a superimposed impact plate laid directly thereon for contact with the table above and the shock absorbing material below, and resilient retaining means therefor.

3. In a molding machine, the combination with a supporting base having a central plunger cavity, outer upwardly projecting walls, an intervening flat bearing surface, and 50 a reciprocable table thereon, of a continuous flat layer of shock absorbing material laid on the flat bearing surface of the base, a superimposed impact plate thereon for contact with the table above and the shock absorbing material below, and retaining means therefor providing for limited vertical movement of the impact plate.

4. In a molding machine, the combination 60 with a supporting base having a central plunger cavity, outer upwardly projecting walls, an intervening floor providing a continuously flat bearing surface, and a reciprocable table having a flat bottom extending 65 downwardly between the outer upwardly

projecting walls, of a layer of shock absorbing material laid on the base floor, a jarring plate laid thereon, and holding studs connected directly with the jarring plate extending downwardly through the shock absorbing material and the floor and provided with buffering springs. 70

5. In a molding machine, the combination with a supporting base having a central plunger cavity, outer upwardly projecting 75 walls, an intervening floor providing a continuously flat bearing surface, and a reciprocable table having a flat bottom extending downwardly between the walls, of a layer of shock absorbing material laid on 80 the base floor, a jarring plate laid thereon, and holding studs for the table extending downwardly through the jarring plate and shock absorbing material and the floor and provided with buffering springs. 85

6. In a molding machine, the combination with a supporting base having a central plunger cavity, outer upwardly projecting walls, an intervening floor providing a continuously flat bearing surface, and a reciprocable table having a flat bottom extending downwardly between the walls, of a layer of shock absorbing material laid on the base floor, a jarring plate laid thereon and holding 90 studs for the table extending downwardly through the jarring plate and shock absorbing material and the floor and provided with buffering springs spaced below the underside of the floor providing for a limited upward travel of the table and resulting cushioning 95 resistance. 100

7. In a molding machine, the combination of a supporting base having upwardly projecting walls, and a reciprocable table thereon having a downwardly extending inner bumping portion within the walls and a top extending over the upper wall edges, and provided with a guiding cover plate secured to the edges of the table top and extending downwardly in close fitting engagement with the outer sides of the walls. 105 110

8. In a molding machine, the combination with a rectangular supporting base having a transverse floor, a middle plunger, and upwardly extending walls having inner corner bearing plates, of a reciprocable table engaging said bearing plates and provided with outer protecting and guiding plates secured to its edges and extending downwardly 115 in close fitting engagement with the outer faces of the base walls. 120

9. In a machine for jarring sand molds, a supporting base having an upper floor provided with an air circulating opening, and means establishing communication between said opening and the outside atmosphere including inner vertical walls having openings and an outer wall having an air supply conduit. 125

10. In a machine for jarring sand molds 130

provided with a supporting base having a table supporting floor, an outer closed wall having an air supply conduit intervening apertured supporting walls, spaced inwardly therefrom, and a table supporting floor having an air circulation opening in communication with the air supply conduit of the outer wall aperture.

5 In testimony whereof I hereunto affix my
10 signature.
